[57] CLAIM

The ornamental design for a cosmetic compact, substantially as shown.

DESCRIPTION

FIG. 1 is a front perspective view of a cosmetic compact showing my new design;

FIG. 2 is a side elevational view, the opposite side being a mirror image thereof;

FIG. 3 is a top plan view thereof;

FIG. 4 is a front elevational view thereof;

FIG. 5 is a rear elevational view thereof; and

FIG. 6 is a perspective view in opened position.

Fig. 4.

Fig. 5.
